UNITED STATES PATENT OFFICE

157,925

BOTTLEHOLDER

John C. Todd, Columbia, S. C.

Application March 22, 1949, Serial No. 1,544

Term of patent 14 years

(Cl. D44—29)

To all whom it may concern:

Be it known that I, John C. Todd, a citizen of the United States, residing at Columbia, in the county of Richland and State of South Carolina, have invented a new, original, and ornamental Design for Bottleholder, of which the following is a specification, reference being had to the accompanying drawing, forming part thereof.

Fig. 1 is a perspective view of a bottleholder, showing my new design.

Fig. 2 is a side view thereof.

Fig. 3 is a rear view thereof.

Fig. 4 is a front view thereof.

Fig. 5 is a plan view thereof.

I claim:

The ornamental design for a bottleholder, as shown.

JOHN C. TODD.
